UNITED STATES PATENT OFFICE.

FREDERICK H. OEHlke, OF LORAIN, OHIO, ASSIGNOR TO THE HOFFMAN HEATER COMPANY, OF LORAIN, OHIO, A CORPORATION.

GAS-BURNER.

1,114,021.

Specification of Letters Patent. Patented Oct. 20, 1914.

Application filed December 23, 1913. Serial No. 808,358.

To all whom it may concern:

Be it known that I, FREDERICK H. OEHlke, a citizen of the United States, residing at Lorain, in the county of Lorain and State 5 of Ohio, have invented certain new and useful Improvements in Gas-Burners, of which the following is a specification.

This invention relates to gas burners and is especially adapted for use in connection 10 with water heaters and the like, in which as a rule a number of burners are nested or placed adjacent to each other under the coil or other water vessel. The burner is of course capable of other uses if desired.

15 The object of the invention is to provide an improved burner of the safety diaphragm type, which will not flash back, and in which the diaphragm will be protected from contact of the flame therewith, the diaphragm 20 being covered by a shield, with passages leading to a slot at which ignition takes place, so that the gas does not burn in direct contact with the diaphragm.

A further object of the invention is to 25 provide a burner which will have the advantage of the flat type, that is, a number of burners can be set close together, retaining however the use of a circular diaphragm through which the air and gas flows, said 30 diaphragm being protected from the destructive action of the heat. The construction is such that the diaphragm can be easily renewed or replaced when necessary, by taking off a cap at the top of the burner.

35 The invention is illustrated in the accompanying drawings in which—

Figure 1 is a side view of the burner. Fig. 2 is a top view. Fig. 3 is a vertical section on the line 3—3 of Fig. 2. Fig. 4 40 is a section on the line 4—4 of Fig. 1. Fig. 5 is a section on the line 5—5 of Fig. 1. Fig. 6 is a vertical section of a modification.

Referring specifically to the drawings, 6 45 indicates a mixing tube which has a bell 7 at the lower end into which the gas nipple 8 projects, the bell having openings indicated at 9 at the bottom, to admit the air to the mixing tube, where it mixes with the gas. The upper part of the tube connects 50 with a shell 6^a which has hollow flattened lateral extensions 10 at opposite sides, which give the burner a relatively flat or elongated shape.

The cap 11 is substantially V-shaped in 55 cross section, to provide outlets on opposite

sides thereof. This cap has on the outer surface of its inclined sides a plurality of vertical ribs 13, with spaces or channels 14 therebetween. The lower ends of these ribs 13 rest on the upper edges or margin of the shell 6^a and its extensions 10, and the grooves or channels 14 are sufficiently deep to form outlets from the space within the burner head. The ribs are continued or extended below the base of the cap to form cross ribs 65 or lugs 15 which fit between the side walls of the extensions 10, and so position the cap on the burner head. The middle part of the cap is expanded or extended to substantially circular form, as indicated at 16, to correspond with the curved shape of the upper end of the shell or casing, said expanded or curved part being also provided with the ribs 13 which, however, terminate at the line of the top of the burner head, lacking the 70 extensions 15 on the ribs which rest upon the extended parts 10 of the head. The cap is held in place by screws 17 engaging lugs 18 at the ends of the cap and burner shell.

The perforated diaphragm is indicated at 80 20 and has the form of a cylinder the lower end of which rests on a shoulder 21 at the upper end of the mixing tube 6. Above this shoulder the shell is enlarged as indicated at 6^a forming an annular chamber which 85 surrounds the diaphragm 20, this chamber communicating with the interior of the lateral extensions or wings 10.

In the form shown in Figs. 1 to 5 inclusive, the lower part of the cap 11 has at 90 the middle thereof a depending circular part or boss 22 which is reduced as indicated at 23, the reduced part fitting within the upper end of the cylindrical diaphragm 20, the diaphragm being thus supported and held in central position by the boss 22 at the top and the shoulder 21 at the bottom. The gas and air passing up through the tube 6 flows through the diaphragm into the annular chamber 6^a and the lateral wings 10, 100 from which it passes up through the grooves 14, combustion taking place where it issues over the lip or edge of the shell. The upper end of the diaphragm 20 is located below said edge and consequently combustion does 105 not take place in contact with the diaphragm, but at the point of exit between the ribs 13, at opposite sides of the burner.

In the form shown in Fig. 6, instead of the boss 22, the underside of the cap has a 110

recess surrounded by a depending flange 25, within which the upper end of the diaphragm fits and is held.

With either form of burner the cap can be removed by taking out the screws 17 and lifting the cap, and the diaphragm will come with it, or can be picked out at the top.

As stated above the extensions 10 provide a large outlet space, and the burners can nevertheless be assembled or set quite close together if necessary or desirable.

I claim as my invention:

1. A gas burner having a hollow flattened elongated shell with an enlarged chamber at the middle, a cap on said shell with discharge openings at opposite sides thereof, a mixing tube opening into said chamber, and a hollow perforated cylindrical diaphragm connecting at its lower end to the upper end of the tube, said cap having a projection on its under side engaging the upper end of said diaphragm to hold it in position and said diaphragm being located within said chamber and spaced on all sides from the walls thereof.

2. A gas burner having a hollow shell, a cylindrical perforated diaphragm within said shell, the upper end of the diaphragm being below the upper edge of the shell, a mixing tube opening into the lower end of said diaphragm, and a cap on the shell, the cap having a projection on its under side,

depending into the shell and engaging the upper end of the diaphragm.

3. A gas burner comprising an elongated shell enlarged at the middle, a hollow perforated diaphragm located in said enlarged part, and spaced from the walls thereof, and a cap over the shell, having ribs on opposite sides thereof resting on the shell and forming discharge grooves between the ribs, said cap having depending ribs on the under side thereof, fitting within the shell, and also having a projection at the middle engaging said diaphragm.

4. A gas burner of the flat type, comprising an elongated flattened shell provided with an enlarged chamber at the middle, a mixing tube communicating with said chamber, said shell having outlet openings at opposite sides of the top, a cap upon said shell, and a tubular perforated diaphragm located within said middle chamber and spaced therefrom entirely around the same, the lower end of said diaphragm resting on the bottom of the chamber in line with the mixing tube, and the upper end of said diaphragm being closed and held in position by the cap.

In testimony whereof, I do affix my signature in presence of two witnesses.

FREDERICK H. OEHLKE.
